H. Putnam Smith

UNITED STATES PATENT OFFICE.

WALLACE C. SABINE, OF BOSTON, MASSACHUSETTS, ASSIGNOR TO H. W. JOHNS-
MANVILLE COMPANY, A CORPORATION OF NEW YORK.

SOUND-ABSORBING WALL OR CEILING.

1,205,938.

Specification of Letters Patent. Patented Nov. 21, 1916.

Application filed November 29, 1915. Serial No. 64,149.

To all whom it may concern:

Be it known that I, WALLACE C. SABINE, a citizen of the United States of America, residing at Boston, county of Suffolk, State 5 of Massachusetts, have invented certain new and useful Improvements in Sound-Absorbing Walls or Ceilings, of which the following is a specification.

My invention relates generally to the prevention or correction of a certain class of acoustical difficulties arising in auditoriums, lecture rooms, offices and the like and due to excessive reverberation, echo, and injurious focusing of sound and similar causes.

More specifically my invention is designed to produce a type of wall or ceiling surfacing or covering which shall be of the highest efficiency in the absorption of sound and consequent diminution of reverberation and 15 echo, and also be suitable for use in auditoriums, class rooms, offices and similar rooms, where a finished and decorative surface is desired.

In some aspects the present invention is 20 an improvement on that disclosed in U. S. Letters Patent No. 1,119,543, granted Dec. 1, 1914, to Rafael Guastavino and myself as joint inventors of an improved wall or ceiling for auditoriums and the like, having in 25 combination a supporting masonry structure and attached thereto an exposed inner layer of finished masonry, sponge-like in structure, the latter having pores which have rigid walls and are inter-communicating throughout the mass and openly penetrate the exposed finished surface, the said pores being of such proportional and 30 variant dimensions that said inner masonry material possesses the property of absorbing 35 in excess of ten per centum of sounds lying in pitch between middle C and a third octave above the middle C. While the said patented invention has proven successful 40 within a certain field of use the surface appearance produced thereby is not such as is 45 always desirable on the walls and ceilings of relatively small rooms where the wall and ceiling surfaces are so near to the inmates 50 as to clearly disclose their surface texture, and the necessity for keeping down the porosity of the surface material described in 55 the patent within certain limits on account of similar considerations of external appearance also limits its acoustical efficiency.

which is directly proportional to such porosity.

Briefly stated, the present invention consists in the combination of porous masonry material of the general type disclosed in the prior patent referred to and an outer sound absorbing and transmitting fabric which is capable of producing a variety of decorative effects, and also of concealing the less attractive porous material behind it. As examples of such covering fabric, I 60 would mention unsized burlap, rep, and other textiles, though other fabrics could be used. This combination of a porous fabric with a porous masonry material,—the latter having pores intercommunicating and of 65 variant dimensions—results in an increased absorbing power and the better correction of acoustical difficulties in auditoriums, offices, and the like, gives a more finished and decorative surface, and permits a less expensive and an acoustically more efficient masonry beneath. The resultant combination permits the use of an unfinished porous masonry behind the textile material without 70 reducing the decorative effect, and thereby reduces cost. It also permits the use of a more porous material similarly without reducing the decorative effect and thereby increases the acoustical efficiency in that factor. The porous textile, or similar fabric 75 used for surfacing is itself capable of absorbing a portion of the sound and of transmitting a very large proportion of sound not so absorbed to the absorbent masonry beneath, thereby further heightening the 80 acoustical efficiency of the combination.

The best form of construction embodying 85 my invention at present known to me is illustrated in the accompanying sheet of drawings in which—

Figure 1 is a cross section of a wall treated in accordance with one manner of applying my invention, and Fig. 2 is a similar view showing a wall treated in accordance 90 with another manner of applying my invention.

Throughout the drawings like reference characters indicate like parts.

1, is the main wall structure or backing 95 which may be of any ordinary building material giving the desired strength and general structural qualities.

2, 2, are sections or panels of porous sound

absorbing masonry material such as is disclosed in Patent No. 1,119,543 before referred to, which are set in cement 3. Over the surface so formed is extended the porous 5 sound absorbing fabric 4, usually a textile, which may be fastened to battens 5, 5, or otherwise secured to the exterior of the masonry, and which forms the interior surfaces of the room exposed to view by the occupants. Preferably the fabric 4, is stretched 10 under a light tension sufficient to maintain a plane surface thereof, and the battens are offset from the face of the wall proper so as to leave a narrow air space between the face 15 of the masonry material 2, and the back of the fabric 4. In the construction shown in Fig. 2, the main wall 1, has a surface capable of receiving and holding nails, and the sections or panels of porous sound absorbing 20 masonry 2, are held in place by nails 6, 6. This cheap and rapid method of attaching the porous masonry to the supporting wall is rendered permissible by my invention without diminishing the decorative effect be- 25 cause the outer decorative fabric 4, covers up the nail heads.

The operation of my invention is easily understood from the foregoing description.

When the sound waves strike the outer 30 fabric 4, a part thereof are absorbed thereby, while other portions are transmitted to the porous masonry 2, behind the decorative covering, and are absorbed thereby or transmitted to the main wall 1.

35 Among the advantages of a wall or ceiling constructed in accordance with this invention may be mentioned the fact that the desired absorption of sound and the correction of acoustical difficulty are obtained to a degree greater than by the use of the masonry material alone or of the textile covering alone, and that the finished surface is smooth and of a texture acceptable in small rooms and in many places where an exposed ma-

sonry surface would be architecturally in- 45 congruous and unacceptable.

Various changes could be made in the details of the preferred construction herein shown and described without departing from the substance of the invention so long as the 50 principle of arrangement and operation of parts above set out, is retained.

If desirable for any reason the textile fabric may be hung more loosely than is indicated in the drawings and may come in 55 contact with the porous masonry beneath. The porous masonry also may be made in other forms, and by a different process from that described in Patent No. 1,119,543 hereinbefore referred to, and applied to the wall 60 while in a plastic condition, subsequently hardening and setting.

Having described my invention, I claim:

1. A sound absorbing wall or ceiling comprising in combination a layer of porous 65 sound absorbing masonry material having a surface broken by open pores and devoid of decorative finish, and a single outer covering of fabric capable of decorative treatment and which is sound absorbing and transmitting by reason of pores passing therethrough from surface to surface.

2. A sound absorbing structure comprising in combination a wall or backing provided with a layer of porous, sound absorbing masonry material, a single outer covering of fabric capable of decorative treatment and porous throughout which is stretched under sufficient tension to maintain a plane 75 surface located parallel to the masonry surface, and a series of widely spaced supports for said fabric which project from the wall slightly beyond the surface of the porous masonry.

WALLACE C. SABINE.
